[57] CLAIM

The ornamental design for a popcorn vending machine, as shown and described.

DESCRIPTION

FIG. 1 is a front perspective view of a popcorn vending machine showing my new design;

FIG. 2 is a front elevational view thereof;

FIG. 3 is a right side elevational view thereof, the left side being a mirror image of the right side shown;

FIG. 4 is a rear elevational view thereof;

FIG. 5 is a bottom plan view thereof;

FIG. 6 is a top plan view thereof;

FIG. 7 is a front perspective view of a second embodiment of the popcorn vending machine;

FIG. 8 is a front elevational view of FIG. 7;

FIG. 9 is a right side elevational view of FIG. 7 the left side being a mirror image of the right side shown;

FIG. 10 is a rear elevational view of FIG. 7;

FIG. 11 is a bottom plan view of FIG. 7; and

FIG. 12 is a top plan view of FIG. 7.
